FIG. 8

FIG. 1

FIG. 4

FIG. 2

FIG. 5

FIG. 3

FIG. 6

FIG. 7

FIG. 1 is a perspective view of an information plate for a test tube or the like embodying my new design; FIG. 2 is a top plan view thereof;

FIG. 3 is a bottom plan view thereof;

FIG. 4 is an elevational view taken from one end thereof;

FIG. 5 is an elevational view taken from the end opposite that shown in FIG. 4;

FIG. 6 is an elevational view taken from one side thereof;

FIG. 7 is an elevational view taken from the side opposite that shown in FIG. 6; and

FIG. 8 is a cross sectional view taken on line 8—8 of FIG. 1.

The plate portion is encoded by punching out the bottom of the selected ones of the blind bores best illustrated in FIG. 8.

I claim:

The ornamental design for an information plate for a test tube or the like, substantially as shown.
